UNITED STATES PATENT OFFICE.

ALBERT HUPP, OF WASHINGTON, DISTRICT OF COLUMBIA, ASSIGNOR TO HUPP AUTOMATIC MAIL EXCHANGE COMPANY, OF WASHINGTON, DISTRICT OF COLUMBIA, A CORPORATION OF DELAWARE.

RAILWAY MAIL-CRANE.

1,229,191.

Specification of Letters Patent.

Patented June 5, 1917.

Application filed October 29, 1913. Serial No. 798,080.

To all whom it may concern:

Be it known that I, ALBERT HUPP, a citizen of the United States, residing at Washington, District of Columbia, have invented 5 certain new and useful Improvements in Railway Mail-Cranes, of which the following is a specification.

This invention relates to mail cranes adapted to deliver mail to a moving train. 10 The invention has for its objects the provision of an improved crane which is adapted to be loaded or to have the bag secured thereto when the arms are in their inoperative position, and to have the arms then 15 swung to a position to deliver the mail bag, and in which the arms are automatically secured in this position.

It is a further object to provide a latching means which is automatically set when the 20 bag is placed on the arms and which is automatically released when the bag is delivered so that the arms will be free to be swung to their inoperative position.

A further object is to provide improved 25 means for swinging the arms from the operative to the inoperative position.

Other objects, and the features of novelty 30 will be apparent from the following description, taken in connection with the accompanying drawings, in which:—

Figure 1 is an elevation of a mail crane embodying my improvements, and shown in connection with a mail receiving trough.

Fig. 2 is an enlarged vertical section of a 35 portion of the crane.

Fig. 3 is an enlarged plan with certain parts in section to show the latching mechanism.

Fig. 4 is a section on the line 4—4 of 40 Fig. 3.

Referring to the drawings, 10 indicates generally the frame work of a mail receiving trough, the mail being received from the train on the inclined platform 11. At the

45 rear of the trough the frame work supports an elevated platform 12, and one or more posts 13 which are preferably secured to the platform 12 by means of flanges 14, and extend below the platform and are secured

50 to the frame work by suitable brackets 15. The post 13 has adjustably secured thereon the conical members 16 and 17, these conical members being formed in halves which

are secured together by bolts 18. As will be seen from Figs. 1 and 2, the conical members 16 and 17 are oppositely arranged on the post 13 and support a tubular member 19 which is rotatable thereon, the conical members serving as bearings for the ends of the tubular member. By having the members 16 and 17 of conical form and adjustable on the post 13, it is possible to readily take up any wear in the parts and to also hold the tubular member 19 in such a manner as to prevent rattling thereof.

Secured on the tubular member 19 are the flanges 20 and 21, the flange 20 having pivotally supported thereon arms 22 and 23 and the flange 21 having pivotally supported thereon the arms 24 and 25. As will be seen from the drawings, these arms are of tubular form and have their ends, adjacent the member 19, secured in suitable brackets, each arm and its bracket thus constituting practically one piece. The arms 75 are pivoted to the flanges at 26 and between the ends of the brackets on each pair of arms there is arranged a spring 27 and a bolt 28, the springs yieldingly holding the outer ends of the arms in closed position to secure the mail bag.

From the drawings, it will be seen that the upper pair of arms is shorter than the lower pair, the latter forming a seat for the mail bag, which is shown at A in Fig. 1. 85 As shown in this figure, the upper arms are adapted to pinch the upper part of the mail bag to hold the same in position. At the top of the post 13 is a cap 29 which is adapted to protect the parts from rain, etc.

The arms 22 and 24 are connected together between the tubular member 19 and the mail bag by a tie rod 30, and the arms 23 and 25 are connected by a similar rod 31, these rods reinforcing and stiffening the 95 arms.

The tubular member 19 is adapted to be rotated on the conical members 16 and 17 to move the arms from the inoperative position, usually at the rear of the post 13, to 100 the operative position shown in Fig. 1, and in order to hold the tubular member 19 with the arms in the position shown in Fig. 1, I have provided in one of the arms, as the arm 25, a latch member 32, the inner end of 105 which is tapered to engage a suitable open-

ing 33 in the post 13. A plunger 34 is slidably arranged in the tube 25, and has connected therewith a rod 35 having an offset portion 36 which extends through a slot 37 in the arm and projects across the space between the arms 24 and 25. (See Fig. 3.) The portion 36 of the rod 35 being approximately at the ends of the arms 24 and 25, it will be obvious that in order to insert the edge of the mail bag between these arms for the purpose of securing the bag, it will be necessary to move the rod 35 toward the post 13. There is arranged between the latch member 32 and the plunger 34 a compression spring 38, and when the rod 35 is moved toward the post 13 this spring is put under compression which will force the inner end of the latch member into the opening 33 when the tubular member 19 is turned to move the arms to the position shown in Fig. 1. The pinching of the mail bag by the arms 24 and 25 so holds the bag that the rod 35 is held in opposition to the spring 38, but when the bag is delivered to the train, the spring 38 forces the rod 35 outward to the position shown in Fig. 3, and is thus relieved of its compression, the latch member 32 being as a consequence free to become disengaged from the opening 33.

30 In order to automatically turn the tubular member 19 so as to move the arms to the inoperative position and hold them there, I have provided in the annular space between the post 13 and the tubular member a torsion spring 39, the end 40 of which is secured to the post 13, the end 41 being secured to the tubular member. When the arms are in their inoperative position, the spring 39 is without tension, but the operation of swinging the arms to the operative position puts this spring under tension and the arms are held in their operative position, in opposition to the tension of the spring 39, by the engagement of the latch 32 with the 45 opening 33 in the post.

Each pair of the arms is provided with a small bracket 42 which bridges the space between the arms and limits the extent to which the bag may be inserted.

50 It is believed that the foregoing description will render the operation of the crane clear without a detail description and this has, therefore, been omitted.

Having thus fully described my invention, 55 what I claim is:

1. In a mail crane, the combination of a post, spaced conical members adjustably secured thereon, a rotatable tube having its ends bearing on said members, and arms on said tube adapted to support a mail bag.

2. In a mail crane, the combination of a post, a tubular member rotatably supported thereon, bag supporting arms secured on said tubular member, a spring pressed latch 65 extending into the said tubular member to

coact with the post therein to hold the latter with said arms in position to deliver a bag, and a spring pressed member carried by one of said arms and operatively connected with said latch.

3. In a mail crane, the combination of a post, a tubular member rotatably supported thereby, bag supporting arms secured on said tubular member, a spring pressed latch coacting with said post and said tubular member to hold the latter with said arms in position to deliver a bag, and a spring pressed member mounted on one of said arms, so as to be moved by the bag when the latter is attached to the arm, and operatively connected with said latch. 70 75 80

4. In a mail crane, the combination of a post, a tubular member rotatably supported thereby, bag supporting arms secured on said tubular member, a latch coacting with said post and said tubular member to hold the latter with said arms in position to deliver a bag, a member mounted on one of said arms and arranged to be moved by the bag when the latter is attached to the arm, and yieldable connecting means between said member and said latch. 85 90 95

5. In a mail crane, the combination of a post, a tubular member rotatably supported thereby, bag supporting arms secured on said tubular member, a latch carried by said tubular member and adapted to engage a part of said post to hold the tubular member with said arms in position to deliver a bag, a member slidably mounted on one of said arms and arranged to be moved by the bag when the latter is attached to the arm, and a spring coacting with said member and said latch to hold the latch in engagement with the post when a bag is attached to the arms 100 105 and adapted to restore said member and release the latch when the bag is delivered.

6. In a mail crane, the combination of a post, a tube rotatable thereon, arms on said tube adapted to support a mail bag, a latch 110 for holding said tube with the arms in position to deliver a mail bag and adapted to be set by the securing of the bag to said arms and released by the delivery of the bag, and a torsion spring connected with the tube and 115 the post and adapted to turn the tube to move the arms to the inoperative position after the delivery of the bag.

7. In a mail crane, the combination of a post, a member supported thereby and having vertically spaced arms, the upper of said arms being the shorter and the lower being adapted to form a seat for a mail bag. 120

8. In a mail crane, the combination of a post, a tubular member rotatably supported thereon, bag supporting arms arranged on said member, a latch carried by one of said arms, a spring having one end in engagement with said latch, and a plunger carried by said arm and engaging the opposite end 125 130

of said spring and adapted to be moved toward said post to compress the spring by the securing of the mail bag to said arms.

9. In a mail crane, the combination of a post having a latch opening, a tubular member supported on said post, bag supporting arms pivoted to said tubular member, a latch carried by one of said arms and adapted to engage said opening to prevent the tubular member from turning, a plunger movable longitudinally of said arm, and a spring between said plunger and said latch, said plunger being adapted to be moved to compress said spring by the securing of the mail bag and being forced in the opposite direction to relieve the compres-

sion of said spring when the mail bag is delivered.

10. In a mail crane, the combination of a post, a tubular member rotatably supported thereby, bag supporting arms secured on said tubular member, releasable means for holding said tubular member in position to deliver a bag comprising a latch member extending into the tubular member to coact with the post therein.

In testimony whereof I affix my signature in presence of two witnesses.

ALBERT HUPP.
